(57) **CLAIM**

The ornamental design for a bathrobe, as shown and described.

DESCRIPTION

FIG. 1 is a front perspective view of the bathrobe, showing the new design;

FIG. 2 is a rear perspective view of the bathrobe thereof; FIG. 3 is a front elevational view of the bathrobe thereof; FIG. 4 is a rear elevational view of the bathrobe thereof; FIG. 5 is a right side elevational view of the bathrobe thereof;

FIG. 6 is a left side elevational view of the bathrobe thereof; FIG. 7 is a top plan view of the bathrobe thereof; and, FIG. 8 is a bottom plan view of the bathrobe thereof.

The short dash broken lines are used to illustrate stitching on the bathrobe and form part of the claimed design. The broken lines shown around the perimeter of the interior of the bathrobe represent boundaries of the claim and form no part of the claimed design.
